UNITED STATES PATENT OFFICE.

LOYD A. RULEY AND ORVILLE F. OSBURN, OF HELENA, OKLAHOMA.

TOOL.

1,388,062.

Specification of Letters Patent. Patented Aug. 16, 1921.

Application filed June 26, 1920. Serial No. 391,961.

To all whom it may concern:

Be it known that we, LOYD A. RULEY and ORVILLE F. OSBURN, citizens of the United States, residing at Helena, in the county of 5 Alfalfa and State of Oklahoma, have invented new and useful Improvements in Tools, of which the following is a specification.

This invention relates to a tool mainly 10 designed for removing and replacing bushings in automobile pistons and the like, the principal object of the invention being to provide means for forcing the bushing into or out of place by a screw device which has 15 screw threaded engagement with a seat member so that the movement of one part toward the other part will force the bushing out of the opening or into the opening, as the case may be.

20 Another object of the invention is to provide a plurality of ferrules or sleeves of different sizes, any one of which is adapted to be passed over the screw member and to fit in the bushing, said ferrule transmitting 25 the pressure of the screw member to the bushing.

This invention also consists in certain 30 other features of construction and in the combination and arrangement of the several parts, to be hereinafter fully described, 35 illustrated in the accompanying drawings and specifically pointed out in the appended claims.

In describing the invention in detail, reference will be had to the accompanying 40 drawings wherein like characters denote like or corresponding parts throughout the several views, and in which:—

Figure 1 is a view, with parts in section, 45 showing the tool being used to force a bushing from a piston.

Fig. 2 is a similar view showing the device being used to place a new bushing in a piston.

Fig. 3 is a detail view of the tubular receiving member.

Fig. 4 is a detail view of the screw threaded member for coöoperating with the screw threaded spindle for forcing the bushings

50 into place.

In these views 1 indicates a piston which is provided with the inwardly extending sockets 2 for receiving the bushings to hold the wrist pin in place. The object of our 55 invention is to provide means for removing

the old bushings when worn or broken and inserting new ones. As shown the device comprises a spindle 3 having a reduced lower part 4, a portion of which is provided with screw threads 5. The head 6 of the spindle 60 has an opening 7 therein to receive a handle 8 by which the spindle may be turned. A plurality of ferrules or sleeves 9 of varying sizes are provided, any one of which may be placed on the reduced part of the spindle 65 with its upper end engaging the shoulder formed at the junction of the reduced part with the main part of the spindle. The upper end of each ferrule is provided with a flange 10. The cylindrical part of the ferrule is adapted to enter the bushing while the flange engages the end thereof. The spindle is made of sufficient length as to extend entirely through the piston as shown in the drawing and when the bushings are to 70 be removed a socket member 11 is used with the spindle, this socket member having its large end curved to conform to the curved wall of the piston to form a seat for said piston. The socket in said member is made 75 large enough to receive the bushing. The socket member is provided with a flattened extension 12 which has a screw threaded bore therein and which is adapted to be placed between the jaws of a vise as indicated at 13. It will thus be seen that when the socket member is placed in a vise and the piston placed on its curved end, the spindle 80 may be passed through the bushings of the piston with its screw threaded end engaging 85 the screw threaded bore in the socket member. Before the spindle is placed in position the ferrule of proper size is placed on its reduced part with the cylindrical part of the ferrule engaging the bushing. Then by 90 screwing the spindle into the socket member pressure will be exerted against the ferrule to cause the same to press upon the bushing and thus force said bushing out of the piston and into the socket member.

After the bushings have been removed from the piston and it is desired to insert new ones a member 14 has its stem 15 placed in the vise with its enlarged part 16 located under the inner end of one of the sockets 2 100 of the piston. This enlarged part is provided with a screw threaded bore 17 and a counter-sink 18, this counter-sink being of a size to receive snugly the end of the bushing. The proper sized ferrule is then 110

2
dropped in the new bushing with its flange engaging the top of the bushing and then the ferrule is placed on the spindle and the screw threaded part of the spindle placed in engagement with the screw threaded bore 17 of the member 14. Then the spindle is rotated so as to cause the threads thereon engaging the bore of member 14 to feed the parts downwardly and thus cause the ferrule to press the new bushings into place.

10 It will of course be understood that our tool may be used for removing and replacing bushings wherever desired as we do not wish to be limited upon its use on automobile pistons or other parts.

15 It is thought from the foregoing description that the advantages and novel features of our invention will be readily apparent.

We desire it to be understood that we may 20 make changes in the construction and in the combination and arrangement of the several parts, provided that such changes fall within the scope of the appended claims.

What we claim is:—

1. A tool of the class described comprising 25 a spindle having a reduced part forming a shoulder with screw threads upon the reduced portion, a flanged ferrule removably arranged on the spindle and having its upper end engaging the shoulder and a supporting member having a screw threaded bore for receiving the screw threaded end of the spindle.

2. A tool of the class described comprising 35 a spindle having a reduced screw threaded part, said reduced part forming a shoulder, a flanged ferrule on the reduced part with its upper end engaging the shoulder and a socket member having a screw threaded bore for receiving the screw threaded 40 part of the spindle and a vise engaging part.

In testimony whereof we affix our signatures.

LOYD A. RULEY.
ORVILLE F. OSBURN.
